ABSTRACT OF THE DISCLOSURE

Apparatus and method for pumping fluid explosives, such as slurries and gels into boreholes includes flow control and hose control. The hose end is kept continuously, as far as practicable, below the surface of the slurry and means are provided for controlled raising of the hose as the hole is filled, to prevent excessive back pressure but to insure keeping the delivery end immersed in the slurry. Where water is not present, this means keeping the hose end below the slurry-water interface to minimize diluting the slurry with water and also to lift the water in piston-like displacement.

Since the introduction of slurry explosives, such as those described in U.S. Patent 2,930,685 and Re. 25,695 by Cook and Farnam, these materials have found increasing utility, particularly in the blasting of hard rock, such as taconite, other iron ores, and the like. It is often difficult, however, to control the placement of these slurries in the blasting site, and particularly in water-filled boreholes. By water-filled boreholes it is intended to mean holes containing liquid water in quantity. In a typical situation, in hard rock blasting, a hole may be bored from five to forty or more feet in depth, with a diameter which may be as small as 2 or 3 inches but is more usually from 6 to 10 inches, or even larger. Holes of the larger sizes are usually spaced at suitable intervals in two directions, the spacing depending on the strength of the explosive and the type of rock being blasted, the degree and kind of breakage desired, etc. A typical spacing is often about 20 to 25 feet in each of two horizontal directions. Large quantities of explosive may be placed in each borehole to fill them to a depth ranging from a few feet to 20 or 30 feet or more. A number of charges may be detonated simultaneously.

As is now well known in the art, these slurry or gel liquid or semiliquid materials are relatively insensitive and quite safe to handle. Preferably, they are pumpable, that is they flow like viscous liquids, and are often and preferably mixed right on site and pumped directly from the mixing operation into the borehole or blasting point. In fact, the pumping of a gel or slurry through a hose or other delivery tube may be an effective continuation of the mixing, since there is a certain amount of shear and intermixing of the ingredients occurring in the slurry as it passes through a conduit. The latter may be a pipe but is usually a flexible hose. However, the materials may be premixed and may be simply forced through the delivery conduit, e.g. a hose, directly into the borehole of the mine.

The pumping of such slurry or gel explosives from a mixing or supply station directly into a borehole involves several problems. The blasting compositions are sufficiently viscous to prevent substantial gravitational segregation of suspended articles from the liquid or semi-liquid menstruum or continuous phase. However, they must not be too viscous to be pumped; on the other hand, once they are in the hole they should not be so liquid that the undissolved components will separate on standing, even on standing for prolonged periods of time.

These slurries, or gels, the terms being synonymous for purposes of this invention, usually contain a thickening agent. Preferably the thickening agent is one which is adequate to prevent serious segregation of the slurry in the hose or conduit but does not become fully effective in its thickening or viscosity increasing function until the material is in the borehole. This thickening agent may be a simple gelling agent such as a gum, a flour, a starch, or it may be a gelling agent plus a cross-linking agent such as sodium or potassium dichromate, borax, or the like. Numerous cross-linking agents are known that are useful. The gelling agent may be either a starch-type thickener, such as wheat flour, tapioca flour, potato starch, etc., or a galactomannin material such as guar gum, or locust bean gum, methyl cellulose, or various other thickeners which are known. In general, the starches and the guar gum are preferred, and mixtures of the materials named above may be used. As is well known in the art, the required amount of thickener depends considerably on the type of material being thickened, the temperature at which it is mixed and used, etc. Typically, guar gum proportions may be from 0.05 to 1% or more, and for starches they may be as high as 5 or 6%. A more typical figure is about 0.5% of thickener when guar gum is used, or 2 to 4% when a material such as tapioca starch is used as a thickener. While water is the least expensive solvent or menstruum, other liquid materials may be added or substituted, wholly or in part. It is often desirable to use small proportions of organic liquids, such as alcohols, glycols, glycol ethers, formamide and its alkylated derivatives and the like, along with water.

For best results, particularly in water-filled boreholes, the slurry should be denser than the water, so that it will settle or rest at the bottom and not float in water. Thus it may have a density of as little as about 1.05 to as much as about 1.8 or more grams per cubic centimeter. A typical slurry of a kind presently preferred has a density between about 1.15 and 1.4 grams per cc., but may be well outside these limits if desired. In any case, for the purposes of the present invention, it should be at least a little denser than water and it should have fairly high water resistance. That is to say, it should not readily be penetrated or leached, even if there is water running through the borehole. The gel or slurry, when it reaches the borehole, should have some structure or water resistance due to the thickener. It should not break up and allow segregation of insoluble components, such as particulate fuels and sensitizers, e.g. particles of metallic aluminum, or of undissolved ammonium nitrate, sodium nitrate, or other inorganic nitrates, chlorates, or perchlorates, or particles of sulfur, carbonaceous particles such as coal or gilsonite, or the like. Any or all of these, or various combinations of two or more of them, may be used in suitable proportions, as is now well known in the art.

Instead of using a pump, a pressure vessel and a supply of compressed air or other fluid may be used to force the slurry through the delivery hose or tube. With a long hose, or one of relatively small diameter, considerable pressure may be required. Hoses may be as small as 1½ inches in diameter and up to several hundred feet long. Pressures as high as 100 to 150 lbs. p.s.i. and more, have been used in some cases to force slurry material into the borehole. Preferably, hoses of larger diameter are used, e.g. 1½ to 2½ inches or more, to reduce pressure requirements. Blasting slurries and gel may be quite thick, even without a gelling agent but it is preferable to use materials which, at the time of pumping, and as they pass through the hose, are sufficiently fluid that they can be pumped into place with moderate pressures at the pump. It is desirable to be able to pump

at pressures which do not substantially exceed about 30 to 40 p.s.i. and it is preferable to use materials which can be pumped at 5 to 10 pounds p.s.i., if their components do not segregate too readily. It is much easier to handle the hose, there is less danger of hose whipping or bursting, or of accidental explosion. When driving the material through the hose pressures up to 100 to 150 p.s.i. or more, which has sometimes been done, the hose becomes very difficult to handle. It will sometimes force itself out of the borehole, even against the holding of one or two strong men, and may spray the explosive material all over the area, and onto the men themselves, with possible serious hazards.

For all these reasons it is preferred to use a mix of low viscosity consistent with stability. A mixture is prepared which has the necessary oxidizer ingredients such as ammonium nitrate, sodium nitrate, and/or chlorates, perchlorates and the like, along with appropriate fuels and/or sensitizers such as powdered aluminum, finely divided coal or gilsonite, sulfur and, including in some cases self-explosive materials previously mentioned, such as particulate TNT, smokeless powder and the like. These may be used sometimes without a gelling agent, when they stabilize against segregation, but it is usually preferred to add a delayed action thickener.

A thickening agent should be used which does not increase viscosity so greatly as to interfere with pumping at reasonable pressures. It should be effective to prevent serious segregation in the flow line, if there is a tendency to segregation. As the material reaches the borehole, it should thicken up sufficiently to prevent substantial segregation of suspended particles and erosion of gel structure even after long standing and in the presence of liquid water.

It is preferable to use a water-resistant thickening or gelling agent. For this purpose, a material such as tapioca flour or guar gum, or a mixture of the two, may be employed along with a cross-linking material or activator to expedite and augment the thickening effect and to minimize the amount of thickening agent required.

In a typical operation, a slurry made up of a liquid, usually a concentrated or saturated solution of an oxidizer salt, is blended in a mixer with dry ingredients which are either insoluble or only partly soluble in the liquid, under the conditions. The resulting slurry is immediately pumped or forced by pneumatic pressure through a hose or other conduit to the borehole, cavity, or point of use, the whole operation taking usually less than a minute—sometimes only a few seconds. It is essential then that the material be suitable in consistency and viscosity to flow under reasonable pressure through the hose, but it preferably increases in viscosity on arriving in the site, being sufficiently gelled or thickened within 15 to 30 or up to 60 seconds or so, that (a) the suspended non-dissolved particles will not separate from the liquid suspending medium in the borehole and (b) the gel will not break down on standing, even in the presence of water. Hence the timing or predetermination of the rate of thickening or gelling is usually very important. A thickener of known properties, such as pre-cooked starch, tapioca flour, etc., or a guar gum, combined with an activator, or accelerator or cross-linking agent of known properties, can be used to get the consistency or structure desired at the time required.

Since the use of a cross-linking agent is often highly desirable, one should be chosen that will give the desired results with reasonable certainty. For purposes of this invention the dichromates such as sodium or potassium dichromate, mentioned above, are particularly desirable. With them a relatively thin slurry which is easy to pump can be fed into the delivery hose, and have good resistance against water leaching or penetration by the time the explosive strikes the water in the borehole, even though the slurry is still quite a thin and pumpable or fluid gel in structure.

Turning now to mechanical considerations, as a rule pumps of considerable capacity are used since it is desirable to fill the boreholes rather rapidly for efficiency of operation. The use of such pumps frequently may tend to introduce undesirable quantities of air into the gel. While a small proportion of air may not be objectionable, and may be even beneficial, it is undesirable to allow the pump to beat large quantities of air into the material. In particular, the process should be so controlled that air in large bubbles or gulps is not introduced into the charge. Such large bubbles may rise through the slurry in a water filled borehole and mix water into it in substantial amounts. To cause mixing at the water-slurry interface may be very detrimental. It causes water dilution, lowered sensitivity, and lowers the resistance to further water penetration. Salts may be washed out and particles of sensitizer materials become separated. These difficulties are more or less proportional to the amount of air pumped with the slurry. It is obvious that these conditions may result in a complete failure to detonate, and in any case will result in a substantial loss of power in the explosion. Aeration of this type due to cavitation at the pump has often been a serious problem in pumping slurries in the past. One aspect of the present invention provides a very satisfactory solution.

The pumping rate of any pump varies with the output pressure. Because slurry is pumped through a long flexible hose which is moved about under many varying conditions, the output pressure may vary constantly and considerably. While there are many obvious ways to maintain the rate independent of pressure, the present inventors found it quite satisfactory to maintain a pumping rate higher than necessary under the highest expected pumping pressure, and by passing or recycling more or less of the slurry from the output back into the input as the occasion demands which avoids pumping air to the delivery line.

It is desirable, and essential in fact, to prevent all unnecessary mechanical mixing of the slurry with water in the borehole. Since such mixing tends to dilute the slurry and to cause it to break down, and possibly fail, or at least greatly reduce its blasting strength, it is important to so handle the slurry that it is introduced first right at the bottom of the borehole. It should be fed at all times so far as practicable by pumping it to a point below the slurry-water interface. This is especially true in boreholes which contain water in quantity. That is to say that if there is water standing in a borehole, to any appreciable depth, or if water is flowing in or through it, the explosive material should be introduced below or under the water as completely as possible. Starting at the bottom of the borehole, or as near the bottom as practicable, the explosive composition should be forced into the hole below or under the standing or flowing water. Thereafter, it should continually be pumped to a hose outlet point which is below the lower water surface in such a manner as to raise the water smoothly with piston-like displacement and with minimum agitation of the water above the slurry, always avoiding intermixing of water with the slurry as far as possible. This means that the end of the conduit or hose through which the slurry is introduced into the borehole should, as far as practicable, be kept below the water-slurry interface. Of course, when the material is first introduced there is no water-slurry interface, but the blasting material should first be introduced right at the bottom of the borehole, or as near thereto as possible.

Since the slurry preferably is denser than the water, and especially if water is present in quantity, the slurry will sink immediately to the bottom of the hole causing the water to rise above it. In any case, mixture of the explosive composition with water should be minimized. The blasting gels and slurries commonly used tend to adhere to the outer hose surface, making it messy

or slippery and hard to handle if covered to any great length. Hence, it is not desirable to continue pumping or slurry delivery with the hose end at the bottom of the hole. Also, the pressure requirements may increase unduly if the hose is not raised as the hole is filled. One aspect of the invention is to avoid these difficulties. To do this, preferably the hose is withdrawn from the borehole at substantially the same rate as the slurry is filled into the borehole. By this, only a small length of hose, say one to three feet, is actually immersed at any time in the slurry. As the slurry rises to a height of say 5, 10, 15, 20 or more feet, only the terminal foot or two of the hose then becomes coated with the viscous slurry. This makes it easier to handle the hose since the viscous gel-like materials are often quite difficult to remove from the hose, in addition to making it very slippery or messy to handle.

The preferred procedure then is to start pumping the slurry as near as practical at the bottom of the hole, delivering it as far as practicable in such a way that the water is merely raised above the slurry, and not substantially intermixed therewith. While it is possible to continue pumping with the end of the hose at the bottom of the hole, forcing the slurry to rise above the outlet of the hose to a distance of a number of feet and lifting the water above that, this procedure is not the preferred one. Not only will a substantial length of hose become contaminated but the load on the pump and on the hose may be greatly increased, particularly with denser slurries. The hose is preferably equipped with a guard over the end so that it will not be jammed into crushed rock or other debris which might plug the hose end or cause difficulty in pumping. With the hose end near the bottom of the hole, pumping is started in such a manner as to force the slurry to the bottom of the hole and raise the water above it. It will be understood that the term "pumping," as here used, includes forcing the slurry through the hose or other delivery tube by any source of fluid pressure. As pumping continues, the slurry rises. The hose then is withdrawn, in the preferred procedure, at more or less the same rate as the hole is filled. Thus, the column of slurry grows, with a rising interface between slurry and water. In this way, only a foot or two of hose is normally actually riding in the slurry, no matter how high the explosive material eventually rises in the borehole.

As is known in the art, it is sometimes desirable to place explosives of high explosive energy at the bottom of a borehole where more energy is required and to place less expensive explosives, with lower energy or explosive density in the higher and top portions of the borehole where there is less burden. This desirable change of composition of the slurry mixture with position in the borehole can be accomplished in the mixer-type pump operation by simply changing the rate of introducing the various ingredients or by changing one or more of the ingredients which are mixed and pumped together. This procedure has great advantages in blasting operations where a more powerful load is needed at the bottom of a borehole, but a less expensive load is satisfactory for the upper part of the charge. According to the present invention, this change of composition as a function of position in the borehole can be made continuously, with the preferred mixer-type pump operation.

The invention will be further understood by reference to a specific embodiment and also to the accompanying drawings which illustrate not only some details of the method described generally above, but also illustrate certain equipment aspects which are of assistance in controlling the borehole filling operation. While reference has been made above to filling of boreholes which contain water, it will be apparent that at least some of the advantages of the invention apply when the holes are dry.

Referring to the drawings, FIGS. 1A, 1B and 1C represent diagrammatically boreholes in rock which contain some water and are to be filled with a pumpable explo-

sive. The various figures show different stages of filling.

FIG. 2 shows diagrammatically a pumping system which includes a hose handling and control mechanism.

FIG. 3 is an elevation at another angle of the hose handling and control mechanism of FIG. 2.

FIG. 4 is a perspective view of the mechanism of FIG. 3, showing certain other parts and omitting some elements.

FIG. 5 is a graphical representation of thickening rates on typical compositions.

Referring first to FIGS. 1A, 1B and 1C, FIGURE 1A shows a typical borehole 10 which may be, say, from about 6 to 10 inches or more in diameter, and of considerable depth. The hole will be ten feet or more deep in many cases, and sometimes as much as forty or fifty feet or more. This hole is shown as containing a substantial amount of water, indicated at 11. Such water may come from natural ground waters or it may have been introduced in the process of boring the hole, since water is frequently used in forming boreholes for blasting, especially in hot jet drilling. In this case, a delivery hose 13 which is of suitable diameter say 1½ to 2½ inches or so, is shown as having been inserted to or very nearly to the bottom of the borehole. The hose is equipped with a guard or screen 15 at the bottom end, in the form of a light open framework of metal attached to the terminal end of the hose in any suitable manner. The purpose of this guard or grid-like screen is to prevent the hose being rammed into a mass of rock or other material which might clog it. In the position shown in FIG. 1A, pumping or other forced delivery may be started, the flowing material coming out of the end of the hose as indicated by the small arrows at the bottom. Thus, the blasting material is immediately pumped to the bottom of the borehole with a minimum of mixing with borehole water.

Referring to FIG. 1B, as the borehole begins to fill with the slurry 17, which is more dense than the water 11, the interface 19 between the slurry and the water rises and the upper surface of the water 21 will rise also unless the water can flow back into the formation, which sometimes happens. Where there is considerable water, it may overflow the hole as the slurry is pumped in to replace it. In any case, as long as there is water above the slurry, excessive mixing of water into slurry, or vice versa, should be avoided. Hence, as far as possible, the end of the hose 13 is at all times kept beneath the slurry and water interface.

In FIG. 1C the operation is continued further, with

slurry 17 filling the borehole to a substantial height. As shown, and as is frequently desirable, a different slurry mix 27 may be introduced after the first slurry mix 17 reaches a desired height, e.g. as indicated at 29. In this case, while mixing of slurry at the pump end is continued, the ingredients are simply changed, either in portions or kind or both, so that a slurry or gel 27 continues to fill the borehole and to push the water above it. The slurry-water interface 19 is at all times kept above the outlet of the hose 13 after enough slurry has been fed to cover it. The extent or length to which the lower end of the hose is held below the interface between water and slurry or gel should not be excessive for reasons pointed out above, but otherwise it is not particularly important, as long as the hose end is low enough that there is not excessive turbulence and intermixing of slurry and water at the interface between the water and the gel. As the hole is filled, the hose is retracted, preferably so that its outlet end will not be so low as to impose heavy resistance to flow on the pump system or on the hose itself. This also avoids contamination of a substantial length of the hose with slurry and, with water above the slurry, the hose can be fairly clean when the hole has been filled and the hose withdrawn.

The procedure shown in FIG. 1C may be continued as far as needed and the composition of the gel or slurry

may be changed more than once, or it can be changed gradually over a continuing period of time, if desirable. In all cases the hose is preferably withdrawn at about the rate at which the hole is filled, preferably continuously at a rate more or less equal to the rate of filling, to prevent excessive contamination of the hose and also to reduce excessive back pressure on the pump. It may be withdrawn intermittently, in small increments, in some cases if desired. A very thick slurry and a long hose can cause considerable flow resistance at the pump and in some cases could possibly result in actual bursting of the hose, not to mention the other difficulties in handling and the dangers inherent in high pressure pumping in such an operation.

The hoses employed in this operation are frequently long and quite heavy. They should be built of sufficient body to withstand substantial pressures. Therefore, it is frequently difficult to handle them manually. For this reason, a hose control apparatus, as illustrated in the lower part of FIG. 2 and FIGS. 3 and 4, facilitates the control and handling of the hose.

This apparatus comprises a powered hose driving reel or drum 51, FIG. 2, mounted on an axle 53 supported in a suitable framework 55 mounted on legs 57. One or more idler wheels, preferably two wheels 59, 61, are mounted in a movable auxiliary framework including a bar 63 and lever 63a in such a way that they can be brought to bear frictionally when desired against the hose which passes over the reel 51. In this way traction can be applied to the hose to keep it in driving engagement with the drum 51. Reel 51, FIG. 4, is preferably driven by a suitable prime mover, e.g. a constant or a variable speed motor 65, through a suitable speed reduction device 67 which may include a drive belt 69 passing over a pulley 71 which is connected in driving engagement with the drum or reel 51. Drive belt 69 preferably is of the timing type. The drive itself may be variable in speed ratio. The arrangement is such that a selectively variable speed may be imparted to the drive of the reel under control of the operator. The operator can cause the reel to turn at the desired hose-raising rate at which the borehole is being filled.

In a typical pumping system, a combination of wet and dry ingredients are fed into a hopper 80 from suitable sources, e.g. a bin of dry material or several bins of such, and a tank of liquid. The liquid is usually an aqueous solution of an oxidizer salt such as ammonium nitrate, sodium nitrate or combinations of the two. It may also include perchlorates or other oxidizers and fuels, e.g. glycols and the like and it may contain a small amount of thickener. The liquid material is preferably introduced in such a way as to minimize contamination of the funnel 80. It may be introduced into a lower funnel element 81 below an edge or flange of funnel 80 to minimize splashing or sloshing into the upper funnel. The dry ingredients flow down the funnel elements 80, 81 to a mixing chamber 82 where a suitable mixer, e.g. of an impeller type 84, driven by a rotary shaft 86, suitably mixes the wet and dry materials together in a smooth or reasonably homogeneous blend. It will be understood that some, and sometimes all, of the dry materials are not soluble in the liquid. These dry ingredients may comprise non-explosives, e.g. aluminum powder, granular oxidizing salts such as inorganic nitrates, etc., sulfur, finely divided coal, gilsonite, or they may comprise explosive materials such as solid particles of TNT, smokeless powder, etc. of appropriate particle size, as is now well known in the art. The ingredients are preferably maintained at a level to provide a hydrostatic head on the pump as indicated at 87, FIGURE 2. A level indicator 89 shows the head.

The mixed materials pass on into a pump shown diagrammatically at 88, preferably of the positive displacement type. The slurry is passed into line 90 and to a 3-way adjustable valve 92. Two ordinary valves may replace valve 92, if desired. From the latter, the stream may be recycled through a line 94, or delivered through hose 13,

or divided so that part flows through both. The material flows through hose 13 to the bottom of a borehole 100 as previously described. The pump has greater capacity than is normally required but the recycle substantially prevents cavitating or pumping air and the valve 92, or two simple adjustable valves, may be set to recycle any desired part of the stream through the by-pass line 94.

Returning to a description of the hose handling mechanism, means are provided for applying frictional pressure to the hose as it rides over the reel 51, through the idler wheels 59 and 61. These wheels are mounted on auxiliary frames which include a member 63. A pivoted lever 110, mounted on a suitable pivotal support 112, has an adjustable toothed rack 114 with an engaging tooth 118 and control elements 116. This lever is used to adjust the position of the idler wheels with respect to the drum or wheel 51. A coil spring 120, FIG. 4, keeps the tooth or detent 118 in engagement with the rack 114 except when the hand grip control elements 116 is operated to release the detent, as is conventional with levers of this type.

When the parts are in the full line position of FIG. 3, the hose is not being frictionally gripped, but the reel is arranged to be driven at a speed which may be controlled as desired, as previously described. If it is now desired to retract the hose, the speed of the reel is set to approximate the speed at which the hole is being filled. This can be judged rather accurately after a little experience. Then the lever 110 is shifted, e.g. to the dotted line position, FIG. 3, to bring the wheels 59 and 61 into frictional engagement with the hose. This causes the rotating reel to pull the hose up out of the hole. By careful control of the withdrawal of the hose in the borehole, only a short length becomes immersed in the slurry. Any water above the slurry-water interface tends to keep the hose clean so that it comes out relatively uncontaminated with the slurry. Of course a short length at the end of the hose may be quite heavily coated with slurry, especially when thick viscous materials are being used. The drive mechanism is preferably made reversible so that it may be used to lay out hose as well as to draw it in, if desired.

The assembly of FIGS. 3 and 4 is relatively light in weight and can be carried if desired or rolled on wheels (not shown), from hole to hole as the hose is inserted and withdrawn for each filling operation.

Instead of mounting a drive motor on this assembly, the speed reduction unit 67 may be driven advantageously through a flexible shaft from a prime mover, e.g. electric motor or a power take-off at the pump truck. A suitable connection is shown for this purpose at 130, FIG. 4. This eliminates the necessity for a separate motor on the hose withdrawal assembly and thereby reduces the weight of the hose handling device. This is advantageous because the terrain on which blasting operations are conducted is often very rough and difficult.

In some operations it may be necessary to reel in or reel out quite a substantial length of hose. For example, in cases where the hole is very deep, and in cases where it is not possible to place the hose lifting unit near the borehole, but it must be at some higher elevation, a substantial load of hose may be involved.

The use of the hose handling equipment of FIGS. 2 to 4 greatly facilitates the borehole filling operation, not only in situations where the hose is too heavy for one man to handle or its length is great, as in the instances just mentioned, but even where the hose could be handled manually. Better control is maintained. It has been found in experience, furthermore, that mine operators generally dislike to handle the hose manually, sometimes because of its heavy weight and also because of the inconvenience, poor footing, etc., at places where the hose is being used.

It is desirable to lift the hose fairly directly, i.e. vertically, from the borehole and not to drag it over or around the sharp edges of rock where the hole is formed. Where this is not possible, a roller or other friction re-

ducing and hose protecting guide can be placed at the edge of the borehole so that the hose can be pulled out from a lateral direction and not from directly above without damage or excessive work. The advantages of the method and apparatus described above still apply.

Obviously a reeling device may be provided in some cases on the truck or pumper unit itself. The pump truck, however, is likely to be at a substantial lateral distance from the borehole, so the use of a reel at the truck often involves pulling the hose over jagged rock at the entrance to the borehole. Frequently this damages the hose. In such a case it is useful again to employ a roller or smooth buffer guide of friction-reducing type at the entrance to the borehole. Such devices form no part of the present invention, but are well known in the art of hose handling. It is preferred, however, where feasible, to lower and lift the hose vertically or as nearly so as convenient. The apparatus shown has real advantages for this purpose.

The whole pumping and hose handling system just described facilitates the orderly filling of boreholes. It gives assurance that the explosive in the hole, particularly in a water filled hole, will be in good condition for the blasting operation. It minimizes the mixing of air and/or water into the explosive. It gives insurance that the product will be homogenous, that the borehole will be thoroughly filled from bottom to the desired top level, all without excessive quantities of water or air or other foreign material diluting the mixture and setting up conditions that may result in blasting failure.

A test explosion was carried out on a mine location where there were 50 foot benches at an elevation above 6,000 feet above sea level. A 9 inch drill hole, 56½ feet deep containing 35 feet of water in the bottom of the hole, was selected for this particular test.

Slurry was pumped at the rate of 400 lbs. per minute. It was desired to change the mix during pumping putting a high energy mix A at the bottom of the hole and a lower energy and less expensive mix B in the upper part of the hole. It was estimated that the hole would contain about 1,000 lbs. of explosives so it was planned to put 400 lbs. of a mix A and 600 lbs. of the less expensive mix B in the hole. The hose consisted of a 50-foot length of 2-inch (inside diameter) hose, followed by 50 feet of 1½ inch (inside diameter) hose. The first 50 feet presents less friction to flow and the last 50 feet is more slender and easier to handle.

In this particular test, the hose operator placed the end of the hose at the bottom of the hole and signaled to the pump truck operator who turned on the controls for the mixing and pumping operation. After one minute of filling with mix A, the mechanism automatically switched to mixing and pumping the lower grade explosive B. Within about 15 seconds after the pump truck operator signaled for the change in mix, the hose man retracted the hose about 5 feet up the hole, as indicated by distance marks on the hose itself. At a pumping rate of 400 lbs. per minute, as calculated, it would take about 14 seconds for the interface between mix A and mix B to traverse the 50 feet of 2-inch hose and 8 seconds additional to traverse the 50 feet of 1½ inch hose, a total of 22 seconds. The bottom of the hose was thereafter raised in increments of about 5 feet by the operator, in such a way that the open end of the hose always remained below the slurry-water interface.

The explosive raised 23 feet in the hole as about 43 lbs. per foot were injected into the borehole. In this particular hole the water was raised just to the top of the hole as it was displaced upward by the denser explosive. Apparently a small amount of the rising water escaped through side fissures, etc.

Immediately after pumping ceased, the hose was withdrawn, completely from the hole. About 3 minutes later,

borehole cuttings were poured into the hole as stemming, replacing a large part of the water which then overflowed the hole.

In this operation the pumping pressure, recorded by a gauge at the pump truck, started at about 25 lbs. per square inch. It later reduced to about 15 lbs. per square inch as the slurry started to fill the bottom of the hole. The pumping pressure increased somewhat, to about 20 lbs. per square inch by the time the last slurry was put into the hole. There may have been some siphoning action at the bottom of the hole after the slurry stream got moving through the hose. It would be expected that this siphoning effect would decrease as the hole became filled, requiring some increase in pumping pressure. Apparently this is what occurred.

The slurry as mixed had an initial temperature of about 56° C., the solution temperature being 65° C. It had a density in the case of mix A of about 1.33 and about 1.27 for mix B. Both compositions of course cooled rapidly in the borehole and this assisted in thickening them quickly. They also contained thickening agents, a small amount of guar gum and a larger amount of tapioca flour, in both mixes. Both contained a small amount of very fine aluminum and some coarser aluminum powder. The total aluminum content was greater in mix A than in mix B.

The viscosity of the materials was determined by a special penetrometer which measures the depth of a conical weight pressing down into the slurry. The first slurry had a penetration of 237, indicating 23.7 mm., and the second of 288 indicating 28.8 mm. As shown in FIG. 5, the thickening rate varied somewhat but in both cases was such as to prevent separation of the solid particles from the slurry by the time it became quiescent in the borehole.

The apparatus of FIGS. 3 and 4 may be modified and made quite automatic by placing at or near the end of the hose a condition sensing means, in the form of elements or a device which will control the hose lifting rate. This sensing device may be a single unit or multiple elements.

These may be either of a pressure type, e.g. one which senses the amount of slurry and water above the end of the hose, or of a temperature sensitive type. The latter is usually preferred. Since the slurry usually has a different temperature from that of the borehole, or of the

water in the borehole, advantage may be taken of this temperature differential. An element sensitive to temperature is designed therefore to control the drive rate of the means which pulls the hose out of the borehole. One temperature sensitive device is indicated only diagrammatically at 140, FIG. 2. This device is of a conventional type

but designed to signal a control element in the speed control at the hose lift mechanism. If the hose is being withdrawn too rapidly, the element 140 gets up into the water, is cooled, or changed in temperature, and gives a signal through line 141 to control mechanism 142, FIG. 2,

to the lift mechanism to slow down the withdrawal operation. The temperature sensitive element 140 may be located preferably at the interface between water and slurry. In this case, with about one to three feet of hose below the

interface 19, the temperature sensitive element being normally located on the hose and at the interface 19 between water and gel, the lifting rate will be maintained automatically by the temperature element. This mechanism may be used also to shut off the hose lift drive motor when the hole is filled. Since some slurry usually will adhere to the hose at the junction, in water-filled boreholes, a definite time interval may be required for slurry to be washed off as the hose is pulled up through the water. The slurry left on the hose thus should either be washed off

to expose the thermocouple or at least it should be sufficiently cooled to de-energize a switching relay in the drive mechanism at the appropriate time. The latter is not shown, being obvious to those skilled in the art. In this case the end of hose-to-junction distance should be adequate to prevent the hose end from being pulled com-

pletely out of the slurry before the retractor or lifter motor is stopped.

After the end of the hose or conduit is covered or buried in the slurry, it is preferably kept continuously below the top of the slurry, even though the hose is being progressively retracted, intermittently or continuously, as the hole is filled. If during any stage of loading the borehole, there is no water, or if the rising water in the borehole should flow off into crevices, which sometimes occurs, to thereby bring the thermocouple or detector point out into air instead of water, the cooling rate of the junction might be too slow to stop the motor before the hose is pulled out of the slurry. This is not serious, however. If water is absent in the hole, there is no problem of mixing water into the slurry. There may still be a possibility of having too much air in the slurry, but this can be avoided by the operator giving reasonable attention to the hose.

In many operations, the borehole is essentially cylindrical and is fairly uniform in dimensions. In the case of jet pierced holes, however, where diameter is not uniform and where it may vary from point to point in the hole, it may be necessary to determine by experience the likely minimum volume of any hole that is to be loaded. The hose or conduit retraction rate in such case should be estimated on the maximum possible slurry rise rate, which is an inverse function of hole diameter. Hose retraction from holes of larger volume preferably should be handled in the manner already described. The constantly varying effective volume per unit length of jet-pierced holes may result in some fluctuations in the slurry rise rate. However, these generally will average out and not cause excessive stopping and starting of the retractor motor which operates the hose lifting operation. Experience will usually help the operator to keep the hose lift at the optimum rate.

Obviously more refined controls may be used if desired. A plurality of thermocouples may be employed, operating at successively different temperatures and depending on ground temperature variations at various depths, as well as for a better control of the hose withdrawal rate. Suitable circuits for such controls may readily be designed by those who are skilled in the art. A signal device also may be incorporated on the hose lifting device, as indicated diagrammatically at 143, FIG. 1, to indicate to the operator whenever any unusual or abnormal situation is arising at the discharge end of the hose. There may, for example, be a large fissure or side opening in the borehole not known to the operator, where excessive quantities of slurry might be pumped and lost or wasted before the operator knows what is going on. Such conditions can be indicated on the device 143 by use of simple sensing means, sensitive to rate of slurry rise, for example, located on the hose. The signal may be of any conventional kind, e.g. either a dial or a light, or a buzzer, indicating abnormal pressure or temperature conditions at the end of the hose.

The use of dual sensing elements 151 and 152, one normally below and one normally above the interface point on the hose (see FIG. 1B) with a communication line 153 to a control box 142A, FIG. 4, can be made instead of the single control 140 described above. In this case if the hose retraction rate is too slow, the upper detector 151, set for water temperature, senses the warmer slurry as it sinks into it and signals the variable speed drive controller 142A to speed up the drive rate and pull the hose up faster. Conversely, if the rate is too rapid, the lower sensing element 152, preset for normal slurry temperature, will rise into the water, sense its different temperature, and signal for a slower withdrawal rate.

As is well known in the art, plastic socks or hole liners may be inserted first into the borehole and then filled to the general exclusion of water or in such a way as to prevent serious loss of the explosive slurry in side holes and fissures. These socks frequently may be punctured, since they are commonly made of thin plastic material

and are subject to dragging over jagged rock edges. Thus they may not prevent completely the intrusion of water. However, they will generally exclude large losses of explosive material.

5 It will be obvious to those skilled in the art that other variations may be made in the method and also in the apparatus of this invention. It is intended by the claims which follow to cover all such variations and modifications as come within the proper broad scope of the invention as indicated by the prior art.

10 What is claimed is:

1. A method of filling a flowable explosive slurry which is denser than water into a borehole containing water, which comprises the steps, in combination, of first introducing the slurry from a forcing station through a laterally unconfined conduit which extends substantially to and has its outlet adjacent the bottom of the borehole, forcing initially a sufficient quantity of slurry to flow to fill the bottom of the hole and to lift the water above the outlet end of the conduit thereby to cover or bury the end of the conduit in slurry, and thereafter withdrawing the conduit upwardly from the borehole while continuing to force the slurry into the borehole, and coordinating the pumping rate and the conduit withdrawal rate so as to keep the outlet end of the conduit at a point substantially always below the top surface of the slurry, thereby to prevent excessive intermixing of water and slurry.

20 2. Process according to claim 1 wherein the end of the conduit is kept submerged in slurry substantially throughout the forcing operation after its end is first buried in slurry but is progressively lifted enough, as the hole is filled, to substantially minimize back pressure at the forcing station.

30 3. Process according to claim 1 wherein a delayed action water-resistant thickening agent is added to the slurry essentially at the forcing station, said agent being timed to become sufficiently effective by the time the slurry reaches the borehole to assist in preventing water leaching of the slurry.

40 4. Process according to claim 1 wherein occluded air passing through the conduit with the slurry is limited to proportions too small to cause substantial mixing at the water-slurry interface or to produce a substantial air gap in the explosive slurry column in the borehole.

45 5. Process according to claim 1 wherein a delayed action thickening agent is added to the slurry essentially at the forcing station, said agent being timed to become sufficiently effective by the time the slurry reaches the borehole to substantially impart water resistance and prevent gravitational segregation of suspended particles from the slurry on standing in the borehole.

50 6. Process according to claim 1 wherein the slurry includes both a gelling agent and a cross-linking agent for the gelling agent.

55 7. Process according to claim 6 wherein the gelling agent is precooked tapioca starch.

8. Process according to claim 6 wherein the cross-linking agent is an alkali metal dichromate.

9. Process according to claim 6 wherein borehole conditions are sensed and the sensation is used to control the withdrawal rate of the delivery conduit.

10. Apparatus for controlling lifting a slurry delivery hose in a water-filled borehole which comprises a driven drum over which the hose passes, adjustable means movable towards and away from said drum for selectively applying driving frictional pressure to the hose in relation to the driven drum, and means for varying the rate at which the drum is driven so that the hose can be controllably withdrawn at a rate not substantially greater than the rate at which the borehole is filled.

11. Apparatus according to claim 10 which includes a sensing element for determining the position of the hose outlet with respect to the upper surface of the slurry in the borehole, and means for affecting the operation of said

rate varying means in response to such determination.

12. Apparatus according to claim 10 which includes dual sensing elements mounted to move with the hose in the borehole, one element being designed to sense when the hose is being withdrawn so slowly as to build up excessive back pressure, and the other element being designed to sense when the hose is being withdrawn more rapidly than the borehole filling rate, and control means responsive to signal from either of said elements to correct the drum drive rate appropriately.
